FIG. 1

FIG. 3

FIG. 2

FIG. 4

Inventor

Thomas L. Bonsall

By *W. Fletcher Haugh Co* Attys

UNITED STATES PATENT OFFICE.

THOMAS L. BONSALL, OF OTTAWA, ONTARIO, CANADA.

MOP.

1,392,741.

Specification of Letters Patent.

Patented Oct. 4, 1921.

Application filed February 7, 1921. Serial No. 443,150.

To all whom it may concern:

Be it known that I, THOMAS L. BONSALL, a subject of the King of Great Britain, and resident of the city of Ottawa, in the Province of Ontario and Dominion of Canada, have invented certain new and useful Improvements in Mops, of which the following is a full, clear, and exact description.

This invention relates to improvements 10 in mops, and the object is to provide a simple, durable and efficient device which may be very easily and quickly manufactured and sold at a low cost.

A further object is to provide a mop in 15 which the cloth is securely held but from which it may be readily removed without the use of tools.

A still further object is to provide a mop in which the cloth is normally held in tension 20 in a frame, the frame being readily adjustable to slacken the cloth for wringing and adjustable with equal readiness to again tension the cloth.

The device consists briefly of a pair of 25 overlapping frame members hingedly connected to one another and to a handle socket, said members being arranged to form a toggle between the ends of which the mop cloth is connected. The two members are provided 30 with means for latching them in position to hold the cloth in tension, which means must be manually operated to slacken the cloth but will be automatically operated by the use of the mop to tension the cloth 35 and latch the frame to hold the cloth in tension.

In the drawings which illustrate the invention;—

Figure 1 is a side view of the device in 40 operative position, the mop cloth being illustrated diagrammatically.

Fig. 2 is a side elevation of the device unlatched to slacken the cloth for wringing.

Fig. 3 is a plan view.

Fig. 4 is a section on the line 4—4, Fig. 3. Referring more particularly to the drawings, 45 11 and 12 designate as a whole a pair of members hingedly connected in overlapping relation by a pin 13. The remote 50 ends of the members are provided with hook-like portions 14, the openings 15 of which are at the tops of the portions and directed toward the hinge pin 13, as clearly shown. A mop cloth 16, which is diagrammatically 55 illustrated, is provided having at the ends enlarged portions 17 adapted to be slipped

in the edgewise direction of the cloth into the hooks 14 and to be therein retained by reason of the enlarged portions 17 being unable to pass through the openings 15 of the 60 hooks. As clearly shown, the cloth passes from the openings of the hooks over the tops and remote portions of the hooks to the under side, the cloth being stretched between the hooks at opposite ends of the 65 frame. As will clearly be seen in Fig. 1, the members 11 and 12 are slightly out of alignment when the cloth is stretched tightly between them, so that the frame constitutes a toggle and downward pressure on its 70 hinge pin 13 will tend to move the hook ends apart and increase the tension of the mop. A handle socket 18 is mounted on the pin 13 and is thereby hingedly related to the frame.

The form of frame illustrated is composed entirely of heavy wire, but it will be understood that the frame may be constructed of other material without departing in any way from the spirit of the invention, although 80 external appearance of the frame may be slightly altered as a result of the different method of manufacture.

Each of the members 11 and 12 comprises a transverse central portion 19 turned at 85 its ends away from the hinge pin and bent approximately in a circular curve in vertical planes to form the hooks 14. From what may be termed the inner ends of the hooks, transverse members 20 extend a short distance 90 toward the longitudinal axis of the frame. At the inner ends of these portions 20 the material is turned at right angles into two substantially parallel, spaced portions 21, which are looped in any suitable manner 95 at 22 to receive the hinge pin and then continued for a short distance beyond the pin in parallelism with the portions 21 of the other member, such continuing portions being designated 23. The portions 21 of either 100 member may be outside the corresponding portions of the other member and, as illustrated, the portions 21 of member 11 lie outside the portions 21 of member 12. The extremities of the outermost parts 23 are 105 turned inwardly as at 24, so as to cross over the portions 21 lying inside them and may be turned slightly downwardly, the purpose being merely to provide rests to support the extremities of one member on the other. 110 The extremities of the inner parts 23 are turned upwardly and then downwardly in

substantially parallel planes to form loops 25 projecting upwardly above the plane of the members 11 and 12. The extremities 26 of the material beyond the loops pass 5 under the portions 23 and are turned outwardly and slightly upwardly to form shallow hooks engageable under the portions 21 of the other member. The lower surface of the hooks may be beveled as at 27, so that 10 the hooks 26 may be forced past the other member, the material between the loops 25 and the hooks 14 yielding to permit passage of the hooks and then returning to original positions to hold the hooks in engagement 15 under the other member.

The handle socket may be conveniently formed of a piece of sheet metal. This metal is looped in its central part around the pin 13, as shown at 28, Fig. 2, and the two 20 end portions are stamped or upset to form semi-circular portions 29 which unite to form the handle receiving socket. Each of the portions is provided at opposite sides with flanges 30 which meet. One flange of 25 each pair is provided with one or more lugs 31 adapted to be turned over the other flange of the pair to connect the flanges and hold the socket in handle retaining form. Obviously the parts 29 may be united by welding or riveting but the method illustrated is 30 preferred as being the least expensive and quite as durable as riveting.

The operation of the device is extremely simple. Assuming the device to be in operative position as shown in Fig. 1 and that it is desired to change the mop cloth or wring the mop, the operator presses the two loops 25 toward one another so as to free the hooks 26 from the other member of the frame. If 40 the mop is held off the floor the weight of the frame and mop cloth will cause the two frame members to swing around the hinge pin so that the cloth hangs in a loop between the members, as indicated in Fig. 2. It will 45 be understood that in Fig. 2 the parts are, for clearness, shown in an intermediate position and that in practice the movement of each member will be through approximately 90°, so that the hooks 14 will come together. If 50 it is desired to remove the mop cloth the enlarged ends 17 are slipped in the edgewise direction of the cloth out of the hooks 14. When the cloth has been squeezed dry, replaced or treated in any other manner desired, the frame is returned to cloth tensioning position by merely pressing the mop 55 down on the floor. When pressed downwardly the members return to the position shown in Fig. 1 and when sufficient pressure 60 is applied the hooks 26 are forced past the parts 21 of the other member and fly outwardly into locking position under the parts, so that the frame is held against return to the position of Fig. 2 when lifted 65 off the floor. The mop cloth is tensioned be-

tween the opposite ends of the frame and is entirely unsupported between the ends of the frame. If more pressure is applied to the handle the toggle frame tends to increase in length and thereby increase the tension in 70 the mop cloth, so that the unsupported central portion presses downwardly on the floor about as hard as the supported ends.

Having thus described my invention, what I claim is:—

1. In mop construction, a frame having hooked end portions, the openings of said hooks being smaller than the space within the hooks, and a mop cloth having enlargements at the ends thereof insertible by longitudinal movement of the enlargements side-wise through the hooks, said enlargements being impassable through the openings of the hooks.

2. In mop construction, a frame comprising a pair of hingedly related members, an extension on each member overlapping the other member, the extension of one member being engageable with the other member to limit relative angular movement of the members in one direction and the extension of the second member being engageable with the other member to limit relative angular movement of the members in the opposite direction.

3. A mop frame comprising a pair of hingedly related frame members, an extension on each of said members overlapping the other member, said extensions being engageable with the members to hold the members against relative angular movement, the extension of one of said members being disengageable from the other member to release the members for relative angular movement.

4. A mop frame comprising a pair of members each comprising a central transverse portion, circularly curved portions at the ends thereof forming hooks disposed in parallel vertical planes, transverse portions extending inwardly from the hook portions in parallelism with the first named transverse portions, side portions extending at right angles to said last named transverse portions, loops formed in said side portions, extensions of the side portions of each member overlapping the side portions of the other member, hooks at the extremities of said extensions engaging the side portions which the extensions overlap, and a pin passing through the loops of said members and hingedly connecting the members.

5. A device according to claim 4, in which the hooked extensions of one member engage the side portions of the other member from above, and the hooked extensions of the second member engage the side portions of the first member from below, said last named hooked portions being disengageable from the side portions.

6. In combination with a device according

to claim 4, a mop cloth having thickened end edges engageable in the first named hooks, said thickened portions being impasseable between the first and second named transverse portions.

7. A device according to claim 4, in which the side portions and extensions thereof in

each member are arranged out of alinement, whereby the members are disposed in angular relation.

In witness whereof, I have hereunto set my hand.

THOMAS L. BONSALL.
